UNITED STATES PATENT OFFICE

162,672

CHILD'S BOBSLED

Harris McBride, Detroit, Mich.

Application July 9, 1948, Serial No. 147,471

Term of patent 3½ years

(Cl. D34—15)

To all whom it may concern:

Be it known that I, Harris McBride, a citizen of the United States, residing at Detroit, in the county of Wayne and State of Michigan, have invented a new, original, and ornamental Design for Child's Bobsled, of which the following is a specification, reference being had to the accompanying drawing, forming part thereof.

In the drawing the figure is a perspective view of a child's bobsled showing my new design.

The characteristic features of my design reside in those portions shown in full lines in the drawing.

I claim:

The ornamental design for a child's bobsled, as shown and described.

HARRIS McBRIDE.
